(57) **CLAIM**

The ornamental design for a gage for press pack clamp, as shown and described.

DESCRIPTION

FIG. 1 is a top perspective view of a gage for press pack clamp, showing my new design;

FIG. 2 is a bottom perspective view thereof;

FIG. 3 is a rear elevational view thereof;

FIG. 4 is a front elevational view thereof;

FIG. 5 is a top plan view thereof;

FIG. 6 is a bottom plan view thereof; and,

FIG. 7 is a left side elevational view, a right side being a mirror image thereof.
